Primary Examiner — Abraham Bahta(74) *Attorney, Agent, or Firm* — BROOKS KUSHMAN
P.C.(57) **CLAIM**

The ornamental design for an over head console as shown and described.

DESCRIPTION

FIG. 1 is left side perspective view of the over head console showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a right side perspective view thereof.

1 Claim, 8 Drawing Sheets(56)
